UNITED STATES PATENT OFFICE.

JOHN W. FOWLER AND DANIEL F. LEWIS, OF BROOKLYN, NEW YORK.

TRIP-SIGNAL FOR FARE-REGISTERS.

SPECIFICATION forming part of Letters Patent No. 247,553, dated September 27, 1881.

Application filed April 30, 1881. (Model.)

To all whom it may concern:

Be it known that we, JOHN W. FOWLER and DANIEL F. LEWIS, citizens of the United States, residing at Brooklyn, in the State of New York, have invented a new and useful Improvement 5 in Passenger-Registers, of which the following is a specification.

The present invention relates primarily to the further improvement of our duplex alarm- 10 register as constructed with a reciprocating setting device; but the subject-matter of this invention may be embodied in any other register in which a rotary trip-hand or any equivalent thereof is or may be adapted to be reset 15 at will, independently of the main actuating mechanism of the register, by means of any setting mechanism having a reciprocating part to coact therewith in any manner, substantially as hereinafter set forth.

20 The general object of this invention is to indicate each resetting actuation of the trip-hand or its equivalent, so as to insure the faithful performance on the part of the conductor or agent of his duty to reset the trip-register at 25 the end of each trip or given period. This has heretofore been accomplished in various ways, a feature common to all being the display of a visual signal or sign in the act of resetting the trip-register.

30 Our present invention consists in indicator mechanism of improved construction adapted to co-operate with a reciprocating setting-slide or the like, and to display in succession such words as "Up, Down," "East, West," "Down, Set, Up," "Hired, Free, Hired," or the numbers of the trips—as, "1," "2," "3," &c., in a superior manner, as hereinafter specified and claimed.

40 In the accompanying drawings, Figures 1 and 2 are small external face-views of an improved alarm-register illustrating the present invention. Fig. 3 is a face view of the same on a larger scale, with the case and dial-plate removed and the parts at rest in the condition indicated by Fig. 1. Fig. 4 is a horizontal section on the line 4 4, Fig. 3, showing a bottom view of the indicator mechanism. Fig. 5 is a vertical section of the register in the central plane indicated by the line 5 5, Fig. 3, illustrating the setting operation. Fig. 6 is a face

view of the main actuating mechanism, alarm mechanism, and indicator mechanism in the condition of the register indicated by full lines in Fig. 2, illustrating the unlocking of the indicator mechanism in the act of sounding the 55 alarm. Figs. 7 and 8 are elevations of the indicator mechanism, as shown in Fig. 6, viewed from opposite edges of the back plate; and Fig. 9 is a section on the line 9 9, Fig. 6, illustrating a detail. Figs. 3 to 9, inclusive, are 60 drawn to one scale.

Like letters of reference indicate corresponding parts in the several figures, and arrows, indicating the motions of parts, are numbered alike in all places.

65 Apart from its main actuating mechanism and alarm mechanism and the novel indicator mechanism aforesaid, the improved register shown in the drawings above described is substantially identical with the subject-matter of 70 our Patent No. 231,161, dated August 17, 1880. The main actuating mechanism and alarm mechanism are substantially of the construction described and claimed in the specification forming part of our application for patent filed 75 October 23, 1880. The specification forming part of the former particularly describes and claims the setting mechanism of the present register, which directly coacts with the indicator mechanism, hereinafter specified and claimed. 80

Referring to our said previous specifications, and to those of our earlier patents therein referred to, for fuller descriptions of the parts described and claimed therein, as aforesaid, the present specification will be chiefly confined to 85 a description of our said indicator mechanism.

In the said drawings accompanying this specification, A and B represent, respectively, the unit-shaft of a trip-register and that of a permanent register; H H², index-hands, carried 90 by said shafts between a dial-plate, d, and the transparent face-plate of a circular case which incloses the several mechanisms; H³, a rotary hundreds-dial, exposing its numbers successively through an orifice, o³, in said dial-plate 95 d; R, a main ratchet-wheel, fast on a shaft, A', equidistant from the shafts A and B; P W W², gearing connecting the shafts A', A, and B, for the transmission of registering impulses from said ratchet-wheel to the unit- 100

hands H H^2 , and through a cam on the wheel W^2 and coacting mechanism to the hundreds-dial H^3 ; X^a , a detent-pawl, engaging with said ratchet-wheel R ; I , a setting-hub, interposed 5 between the trip-hand H and its shaft; J , a radial setting-slide, which coacts with said setting-hub to reset the trip-hand at zero at will; and K , an inwardly-thrusting key, adapted to be inserted through a key-hole, k , in the case 10 to move said setting-slide in one direction, and to put in tension retracting-springs s^3 , as shown substantially in the drawings accompanying the said specification of our Patent No. 231,161; and S represents a main actuating-slide, provided on its back with a stud-pin, which projects through a slot in the back plate of the case, as illustrative means for pulling the same and putting in tension its retracting-spring s^4 ; F , a main working-pawl, carried by said slide 15 S and coacting with the ratchet-wheel R ; E , a distinct bell-lever, actuated by said pawl F and a striking-spring, s^5 , and carrying the bell-hammer h , which strikes a gong-bell, G , after each unit is registered; and D , a swinging 20 catch to prevent ringing the bell until the final act of bringing the parts to rest after each registration, as shown in Figs. 3, 4, 7, and 8 of the drawings accompanying the said specification of our application filed October 23, 1880. 25 S^o Our indicator mechanism which completes said improved register is located behind the dial-plate d , to the left of the bell G , and above the setting-slide J and bell-lever E , an oblong horizontal orifice, o' , being provided in the dial-plate to expose the indicator or visual signal V . This indicator consists, for example, of a wooden parallelopiped, of sufficient length, covered with paper of a color contrasting with that of the dial through which the orifice o' is 30 cut, and printed with the illustrative words "Up" and "Down" on alternate sides thereof, so that the same appear successively through the orifice o' when the indicator is turned upon its longitudinal axis, as illustrated in Figs. 1 and 2. 40 The indicator V is supported, by means of an axial pivot rod or shaft, Z , between the outer ends of a pair of bearing-posts, a b , springing from the back plate, w , so that its axis is 45 parallel to and close behind the dial-plate, as shown in Fig. 5.

A parallel rock-shaft, Y , is mounted behind the indicator in the bearing-post a and a short parallel bearing-post, c , the post b being curved 50 to clear the bell and bell-hammer, and hence not available for this use. This rock-shaft has two lever-arms, l m , made fast thereon in substantially one and the same radial plane. The arm l projects normally in the path of the setting-slide J , as shown in Fig. 3 and in full lines in Fig. 5. The arm m is constructed with a pivoted finger, f , and with a rigid finger, g , as shown most clearly in Figs. 4, 5, and 9, and a lantern-pinion, p , and a stop-square, i , are formed around 60 the shaft Z , at the corresponding end of the indicator V , to coact with said fingers. At the

other end of the indicator the shaft Z is provided with a collar, j , having V -notches in its periphery to receive a projection of corresponding shape at the extremity of a spring-detent, U , which is clamped at its other end to one of the studs, e , on the frame of the setting-slide by means of a drilled hub and set-screw, as shown in Figs. 3 and 8. The rock-shaft Y is extended through the post a to receive an arm, T , which has a drilled hub and set-screw for clamping it in position. The arm proper has a longitudinal recess in one side to accommodate the shank of a spring-finger, n , of elastic wire, which is secured therein at its inner end, 80 so as to yield laterally, while it is substantially rigid in the direction of the movement of the arm, and the bell-lever E is provided with a projection, e^a , having inclined and level surfaces to engage with said finger, as shown in 85 Figs. 4 and 7. A spring, s^v , and a stop-pin, r , attached to the post a , coact with an extension of the arm T above the rock-shaft to return the several arms of the rock-shaft to their normal positions (represented in Figs. 3 and 4 and in 90 full lines in Fig. 5) and to arrest and support them in these positions. By adjusting the arm T on the rock-shaft by means of its set-screw the presentation of the other arms may be readily regulated. With the arms of the rock-shaft 95 Y in said normal positions the setting-slide J , being also at rest, as shown in Fig. 3 and in full lines in Fig. 5, the registering mechanisms and the alarm mechanism are unobstructed and unburdened, and the registering operation proceeds as illustrated by Fig. 1, and by the arrows 1, 2, 3, 4^a, 4^b, 4, 5, 6, and 7, until a trip (the "up" trip, for illustration) is completed. The setting-key K (shown in dotted lines in Fig. 5) is now inserted through the key-hole k in the 100 sheet-metal drum of the case, and the trip-hand H is reset at zero, and the indicator V is simultaneously and by the same means set for another trip, ("down," for example,) as illustrated by full lines in Fig. 2, and in dotted lines in Fig. 105 5, and by the arrows 8^a, 8^b, 8, 9, and 10. The operation of setting the trip-hand is fully described in the said specification of our Patent No. 231,161, hereinbefore referred to. 110 The operation of setting the indicator V is 115 as follows: At each inward thrust of the key K (indicated by arrow 8^a) the setting-slide J is pushed upward until arrested by its stops. During the first of these strokes the slide J comes in contact with the arm l of the rock-shaft Y , and imparts to the various parts of the latter the movement indicated by arrow 9. The pivoted finger f , at the extremity of the arm m , is thus caused to coact with the pinion p , so as to give the shaft Z of the indicator a 120 one-fourth turn, (indicated by arrow 10.) At the completion of this movement the finger g comes in contact with one of the faces of the square i , and stops the indicator with its corresponding face parallel to the dial-plate. The 125 said movement of the arm T causes the spring-finger n to press against the inclined rear sur-

face of the projection e^n until said finger springs over the laterally-projecting edge of the projection, so as to be caught by its flat outer surface when the slide J recedes. The indicator mechanism, as represented in dotted lines in Fig. 5 and in full lines in Figs. 6 and 9, is thus locked, and remains locked during the remainder of the setting operation, offering no obstruction nor additional load to the setting-slide. The special object of thus locking the indicator as soon as it is set is, however, to prevent the disarrangement thereof, which would otherwise occur in setting it by means of the said setting-slide J, or any substitute reciprocating setting device requiring an indefinite number of actuations (varying, in the case of said slide J, from one to three) to reset the trip-hand at zero.

The operation of unlocking the indicator V and restoring the parts of the rock-shaft Y to their normal positions preparatory to setting the former at its next indication at the end of the succeeding trip is illustrated by dotted lines in Fig. 2, by Figs. 6 to 9 inclusive, and by arrows 2, 4^a, 4^b, and 11. This is accomplished by the actuation of the alarm mechanism in the act of registering the first unit belonging to the new trip, so as to render the indicator mechanism at rest as quickly as possible, and to avoid burdening the main actuating mechanism. As the bell-lever E is tripped during the return-stroke of the main slide S, the projection e^n is carried from behind the spring-finger n , and the spring s^v immediately returns the parts of the rock-shaft Y to the positions in which they are shown in Figs. 3 and 4 and in full lines in Fig. 5. The parts are shown in Fig. 6 as they appear at an intermediate period of the said return-stroke of the main slide, (indicated by arrow 2.) The spring-detent U, coacting with the notched collar j , Fig. 8, continues to hold the indicator V, operating to keep the same from turning under jars or jolting. The finger f is pivoted to allow it to recede during the return movement of the arm m , as illustrated by dotted lines in Fig. 9.

The alarm action illustrated by Fig. 6 is fully described, as aforesaid, in the specification of our application for patent filed October 23, 1880, to which we refer.

Arrow 12 indicates the next actuation of the indicator, bringing "Up," in the example, again to the front, to be followed by "Down" at the end of the next trip, and so on.

The indicator mechanism herein described may be used without modification in our register with attached setting-knob, as shown in Figs. 1 to 8, inclusive, of the drawings belonging to our said application filed October 23, 1880, and with immaterial modifications it may readily be adapted for embodiment in other registers having reciprocating setting devices—such, for example, as those illustrated by Figs. 9 to 12 of said drawings belonging to our application filed October 23, 1880.

In adapting the said indicator mechanism to different uses, the lettering on the indicator V will vary, as hereinbefore indicated, and said lettering may, in fact, be wholly omitted, different contrasting colors, for example, being well known substitutes therefor.

The shape of the indicator V, in cross-section, may also be varied without departing from our invention. For example, said indicator may have but three sides, or more than four sides, or it may be cylindrical; and where two indications are to be displayed in succession at each operation, instead of but one, as "Free" and "Hired," or the like, in a cab-register, the spring-detent U and spring s^v , either or both, may be adapted, by well-known means, to impart the required additional movement to the indicator when it is unlocked at the beginning of the new trip.

We do not limit ourselves to details of mechanical construction not essential to the respective features and combinations hereinafter claimed. Neither do we claim, broadly, an indicator combined with setting mechanism, so as to be changed in the act of resetting a trip-hand or its equivalent at zero, such indicators being old—as shown, for example, in British Patents No. 1,217 of 1864 and No. 82 of 1870. Neither do we claim herein anything shown or described in our previous patents, or in our last previous application for patent aforesaid.

What we claim as new, and desire to secure by Letters Patent, is—

1. The rotary indicator V, arranged behind the dial-plate of the register, and adapted to turn on a horizontal axis parallel to said dial-plate to display different indications successively through an orifice in said dial-plate, in combination with the rock-shaft Y, having the arm m , with fingers f g , and the rotary shaft Z, having the pinion p and stop-square i as means for turning said indicator.

2. The adjustable arm T, with its drilled hub and set-screw, and its extension above the rock-shaft, in combination with the indicator-spring s^v and stop-pin r , for regulating the presentation of the other arms of the rock-shaft Y, in the manner set forth.

3. The bell-lever E, provided with the projection e^n , having inclined and bevel surfaces, as specified, in combination with the arm T, having the laterally-yielding spring finger n , for locking and unlocking the rock-shaft Y, in the manner set forth.

4. The combination, substantially as herein specified, of a trip - register, a reciprocating device for resetting said register at the end of each trip, and an indicator mechanism adapted to be fully actuated to change the reading or indication of said indicator at the first stroke of said reciprocating setting device.

5. The combination, substantially as herein specified, of a trip - register, a reciprocating device for resetting said register at the end of each trip, an indicator mechanism adapted to

be actuated by said setting device, and a locking device for preventing repeated actuations of the indicator by said setting device during the individual setting operation.

5 6. The combination, substantially as herein specified, of a trip - register, a reciprocating device for resetting said register at the end of each trip, an indicator mechanism adapted to be actuated by said setting device, an alarm mechanism adapted to interlock with said in-

dicator mechanism during the setting operation, and a main actuating device as means for unlocking the indicator mechanism, in the manner set forth.
